(57) **CLAIM**

The ornamental design for a beaded rabbit vibrator, as shown and described.

DESCRIPTION

FIG. 1 is a perspective view of a beaded rabbit vibrator with the ornamental design;

FIG. 2 is a front elevation view of the beaded rabbit vibrator of FIG. 1;

FIG. 3 is a rear elevation view of the beaded rabbit vibrator of FIG. 1;

FIG. 4 is a side elevation view of the beaded rabbit vibrator of FIG. 1;

FIG. 5 is a top plan view of the beaded rabbit vibrator of FIG. 1; and,

FIG. 6 is a bottom plan view of the beaded rabbit vibrator of FIG. 1.

The broken lines shown in the drawings are for illustrative purposes only and form no part of the claimed design.
